(57) **CLAIM**

The ornamental design for an orthopedic plate, as shown and described.

DESCRIPTION

FIG. 1 is a front/top, left-side perspective view of a first embodiment of the orthopedic plate.

FIG. 2 is a top view of the first embodiment of the orthopedic plate.

FIG. 3 is a rear view of the first embodiment of the orthopedic plate.

FIG. 4 is a front view of the first embodiment of the orthopedic plate.

FIG. 5 is a bottom view of the first embodiment of the orthopedic plate.

FIG. 6 is a left-side view of the first embodiment of the orthopedic plate.

FIG. 7 is a right-side view of the first embodiment of the orthopedic plate.

FIG. 8 is a right-side view of the first embodiment of the orthopedic plate, as viewed in a direction normal to the right-side edge.

FIG. 9 is a front/top, left-side perspective view of a second embodiment of the orthopedic plate.

FIG. 10 is a top view of the second embodiment of the orthopedic plate.

FIG. 11 is a rear view of the second embodiment of the orthopedic plate.

FIG. 12 is a front view of the second embodiment of the orthopedic plate.

FIG. 13 is a bottom view of the second embodiment of the orthopedic plate.

FIG. 14 is a left-side view of the second embodiment of the orthopedic plate.

FIG. 15 is a right-side view of the second embodiment of the orthopedic plate; and,

FIG. 16 is a right-side view of the second embodiment of the orthopedic plate, as viewed in a direction normal to the right-side edge.
